(57) **CLAIM**

The ornamental design for a novelty bottle cap remover, as shown and described.

DESCRIPTION

FIG. 1 is a front elevation view of a novelty bottle cap remover, showing my new design;

FIG. 2 is a bottom plan view thereof;

FIG. 3 is a left side elevation view thereof;

FIG. 4 is a right side elevation view thereof; and,

FIG. 5 is a perspective view thereof.

The broken lines depict environmental subject matter only and form no part of the claimed design.
